UNITED STATES PATENT OFFICE

ARTHUR W. BURKS, OF DECATUR, ILLINOIS

AIR PUMPING CENTRIFUGAL PUMP

Application filed February 7, 1930. Serial No. 426,639.

The present invention relates to rotary pumps of the centrifugal type, and it has as an object the provision of a centrifugal pump which is adapted to pump and compress both gas and liquid.

5 A further object of the invention is to provide a centrifugal pump having an improved impeller construction particularly suited for pumping both gas and liquid, and which is 10 adapted to cooperate with an air separator disposed adjacent the rotor or impeller.

Another object of the invention is to provide an air pumping centrifugal pump which is self-priming, and is adapted to evacuate its 15 supply line as well as to eliminate any air from the pump chamber which may tend to fill the same and reduce the pump delivery during the course of its operation upon liquid.

Another object of the invention is to provide a pump of simple construction having a minimum number of parts, and which may be operated for extended periods without repair, replacement or adjustment of parts.

The foregoing and other objects of the invention will become clearer as the description proceeds in connection with a preferred embodiment shown in the accompanying drawing, wherein:

Figure 1 is an elevational view partly 30 broken away.

Figure 2 is a vertical view on substantially the line 2—2 of Figure 1.

Figure 3 is a plan view partly in section.

Referring to the drawing for a more detailed description, the pump casing comprises sections 10, 11 secured together adjacent their margins, as by bolts 12. The section 11 has a central hollow boss 13 threaded to receive a supply connection 14, the boss 40 serving as an inlet to direct the fluid into substantially the center of a rotor or impeller 15 fixed to shaft 16 which has a bearing in the casing section 10.

The impeller 15 has one lateral wall or 45 shroud 17 which extends from the axis of the

pump to its periphery 17'. The wall carries a plurality of peripherally directed webs 18, in the present instance radially disposed (Fig. 2), the webs forming therebetween peripherally directed passages which have 50 outlets at the periphery of the pump.

Adjacent the margin of the rotor and at their outlets, the passages have positioned therein a plurality of blades 23, which form between one another and with the webs 18, 55 buckets 24 opening laterally, but closed substantially throughout the entire path of travel by the wall 11' of the casing section 11.

The same side of the rotor has a wall or 60 shroud 25 which terminates inwardly from the periphery of the rotor, so as to provide the open sided buckets. This shroud, if desired, may be provided with a plurality of ribs and grooves 26 coacting with complementary ribs and grooves 27 upon the casing section 11.

The rotor buckets and radial passages discharge into a raceway which in the present instance is formed by the opposed facing 70 flanges 28, 28' of the casing sections. This raceway extends between the point 21 and an outlet opening 22 and is provided by directing the raceway forming flanges along a substantially spiral path. Between the points 75 21 and 22, it is on an arc which is eccentric to the rotor axis so as to provide a raceway progressively increasing in radial depth from the point 21 to the discharge 22 in a counter-clockwise direction (Fig. 1). Between the 80 rear edge 22' of the outlet opening and the point 21, the flange follows closely the periphery of the rotor and the edge 22' is beveled so as to laterally deflect the water through the outlet 22. The opposite edge 85 22'' is beveled on its side facing the rotor in order to facilitate the raceway discharge.

It will be clear, therefore, that water drawn through the inlet into the impeller passages between the outlet 22' and the point 21 where 90

the raceway begins, cannot be discharged until the impeller reaches the latter point because the flanges 28 closely follow the periphery of the rotor between the points 22' and the point 21 in a counter-clockwise direction, and for the further reason that the wall 11' of the casing section closely fits against the face of the rotor and the open side of the buckets 24.

10 A chamber 31 is disposed adjacent the raceway, and has an opening 33 in its wall past which the buckets move as the rotor is operated. The chamber has a discharge opening 31' in its top 30', the opening being threaded to receive a discharge connection 32. When liquid is maintained in the chamber, the buckets tend to set up an air separating whirlpool the liquid of which engages the buckets and displaces air carried thereby into the whirlpool. This air is separated from the body of liquid by centrifugal force and discharged through the opening 31.

15 The chamber is also in communication with the raceway 20; in the present instance, this is accomplished by disposing the raceway outlet opening 22 at the chamber, and so that liquid discharged into the chamber from the raceway will enter the chamber tangentially and thereby assist the buckets in maintaining a whirlpool.

20 Water passing through the outlet 22 is discharged tangentially into the chamber, as indicated by the arrow 30. In order that the whirlpool may be set up without the formation of eddy currents at the outlet, the beveled surface adjacent the edge 22' is substantially a continuation of the arc of the inner surface 29 of chamber 31. It will be understood that from the rear edge 21' of the outlet opening 22 and the flange 21' of the outlet opening 22, the flange 28' continues closely against the periphery of the rotor to the point 21 in the direction indicated by the arrow 29' which also shows the direction of rotation 25 of the impeller.

25 When pumping air, it is simply necessary to fill the chamber 28 sufficiently to provide liquid to form a whirlpool, and as the buckets carrying air move past the chamber, the air therein will be displaced into the whirlpool by the liquid. Any water carried off by the buckets from the whirlpool will be discharged therefrom into the raceway 20 as soon as the buckets reach the point 21, and this liquid 30 will follow the raceway and be returned through the outlet 22 into the whirlpool. As soon as the buckets discharge the liquid, they are free to take up air drawn in through the inlet 13, and this air is removed from the buckets as soon as they again reach the whirlpool.

35 It will be understood that there is a constant circulation of liquid from the whirlpool into the buckets from which the same is discharged into the raceway to then pass

back to the whirlpool. The buckets are arranged so as to discharge the liquid and take up air entering the inlet, so that every time they return to the chamber 28, they are filled with air.

The pump may be used for pumping air and water, or a mixture of the two. If during the liquid pumping operation, the pump chamber tends to fill with air, thus reducing the liquid delivery, the air pumping operation described will immediately take place or at least as soon as the water in the pump falls so low that it will not fill the buckets.

40 For the purpose of maintaining the liquid seal between the wall or shroud 25 and the casing 16, there may be provided, if desired, the lateral adjusting means for the rotor disclosed in my Patent 1,686,549, granted October 9, 1929.

45 Moreover, the blades may be of the same form shown in that patent, or may take other forms. They may extend along the exactly radial lines shown (Fig. 2) or may be disposed in planes which are substantially 50 cords of the rotor circumference.

55 In a lateral direction, they may be disposed at right angles to the wall 16, or may be inclined, if desired.

60 Although I refer to the pumped fluid as "air" and "water", it will be understood that these terms are used merely for purposes of example, and to cover respectively any gas or liquid to be pumped.

65 Obviously, numerous modifications may be made in the structure illustrated and described without departing from the invention, the essential features of which are defined in the following claims.

I claim:

1. A pump comprising a rotor having a laterally opening inlet and peripherally directed passages leading therefrom, said passages being laterally closed by a rotor wall on one side of the rotor only part way to the periphery and having at their outlets a plurality of buckets opening both toward said side and toward the periphery, and a casing having a wall closing the buckets and passages at their open sides substantially entirely around the rotor and forming around the rotor periphery a raceway into which said passages centrifugally discharge, said raceway having an outlet, a chamber adapted to maintain an air separating whirlpool and having an opening in its wall through which said buckets communicate with the chamber at said open side of the rotor, said chamber being adapted to maintain an air-separating whirlpool which engages said buckets and displaces air therefrom into the whirlpool, the chamber being in communication with said raceway outlet and being adapted to receive the raceway discharge therethrough.
2. A pump comprising a rotor having a laterally opening inlet and peripherally di-

- rected passages leading therefrom, said passages being laterally closed on one side of the rotor only part way to the periphery and having at their outlets a plurality of buckets 5 opening both toward said side and toward the periphery, and a casing having a wall closing the buckets and passages at said open sides substantially entirely around the rotor and forming around the rotor periphery a 10 raceway into which said passages centrifugally discharge, said raceway having an outlet, a chamber adapted to maintain an air separating whirlpool and having an opening in its wall through which said buckets communicate with the chamber at said open side of the rotor, said chamber being adapted to maintain an air-separating whirlpool which engages said buckets and displaces air therefrom into the whirlpool, the chamber being 15 in communication with said raceway outlet radially beyond the periphery of the rotor and being adapted to receive the raceway discharge through said outlet. 20
3. A pump comprising a rotor having a laterally opening inlet and peripherally discharging passages leading therefrom, said passages being laterally closed on one side of the rotor only part way to the periphery, whereby to provide a lateral passage outlet, 25 and having at their outlets a plurality of buckets opening both toward said side and toward the periphery, the other side of each passage being closed substantially from the rotor axis to the rotor periphery, and a casing 30 having a wall closing the buckets and passages at their open sides substantially entirely around the rotor and forming around the rotor periphery a raceway into which said passages peripherally discharge, said 35 raceway having an outlet, a chamber adapted to maintain an air separating whirlpool and having an opening in its wall through which said buckets communicate with the chamber at said open sides of the passages, 40 said chamber being adapted to maintain an air-separating whirlpool which engages said buckets and displaces air therefrom into the whirlpool, the chamber being in communication with said raceway radially beyond the 45 ends of the buckets outlet and being adapted to receive the raceway discharge through said outlet. 50
4. A pump comprising a rotor having peripherally directed and opening passages, 55 said passages being laterally closed on one side of the rotor only part way to the periphery and having at their discharge portions a plurality of buckets opening both toward said side and toward the periphery, and a 60 casing forming around the rotor periphery a raceway into which said passages peripherally discharge, said raceway having an outlet, a chamber adapted to maintain an air separating whirlpool and having an opening 65 in its wall through which said buckets com-
